UNITED STATES PATENT OFFICE.

ANTHONY SCHROEDER, OF CLEVELAND, OHIO, ASSIGNOR OF ONE-HALF TO JAMES MERLE FINNEY, OF CLEVELAND, OHIO.

ROLLING-DOWN MACHINE.

Original application filed May 20, 1925, Serial No. 31,530. Divided and this application filed June 29, 1927.
Serial No. 202,206.

This invention relates to mechanism for heading or seaming heads on the bodies of metal containers, for example, liquid receiving tanks, storage tanks, barrels, drums and the like and receptacles for dispensing mechanisms.

This application is a division of my application Serial No. 31,530, filed May 20, 1925—see Letters Patent No. 1,635,506, dated 10 July 12, 1927.

One object of the invention is to provide an improved mechanism for rolling down the folded or interlocked portions or flanges of container parts.

15 Another object of the invention is to construct an improved mechanism capable of rolling down a seam formed around the lateral sides of a container body.

Other objects of the invention will be apparent to those skilled in the art to which my invention relates from the following description taken in connection with the accompanying drawings, wherein

20 Fig. 1 is a side elevation of a rolling down machine or mechanism embodying my invention.

Fig. 1^a is a fragmentary section showing the rolling of the seam into final position where the container body is formed with a 30 seam receiving recess.

Fig. 2 is a front elevation of the machine.

Fig. 3 is a rear elevation of the machine. The machine or mechanism embodying the present invention is adapted for rolling into final form or shape the seamed portions or flanges of container parts, one example of such parts comprising the container body and one of its heads. Where these parts are to be connected the seamed portions constitute flanges which have been previously folded or otherwise related, one to the other, so that when they are rolled down by the machine herein disclosed, the seamed portions are compressed or rolled into final position, 40 forming a liquid tight, permanent joint. Certain mechanisms and processes of folding and interlocking the flanges of the body and head are disclosed in my aforesaid application; thereafter the container body and adjacent head are positioned on the machine shown herein (see Fig. 1) and then the container is rotated to effect the rolling down operation, as will later appear.

In the drawings, 55' indicates a frame com-

prising a base and suitable standards mounted thereon. The standards 55 are provided with pairs of bearings 56, 57, the former rotatably supporting a shaft 58 and the latter supporting a rod 59, the purpose of which will later be set forth. At its inner end, the 55 shaft 58 is provided with a gear 60 with which meshes a pinion 61 fixed to a countershaft 62, also mounted in suitable bearings 63 provided on the standards 55. The shaft 62 is provided with fast and loose pulleys 64, 65, arranged to be driven by a belt 66. On its outer end, the shaft 58 is provided with a supporting member 67 having a mandrel 68 on its free end. As shown in this view, the container body A fits over and is supported by the member 67, its head a engaging the mandrel 68. The supporting member 67 may have a diameter approximately equal to the interior diameter of the body or it may be of less diameter and thus be utilized for use in connection with different sizes of container bodies.

The shaft 58 serves to rotate the supporting member 67 and the latter in turn serves to rotate the body due to its engagement therewith resulting from the pressure of a rolling down roller 69 to which reference will later be made. 70 indicates a bracket 70 removably mounted on the free end of the rod 59 and shaped to provide a pair of guides 70^a 85 in which is slidably supported a slide 71. The slide 71 is provided with a pair of depending spaced arms 72, 72^a (the latter being an extension of the base portion of the slide), having bearings for a shaft 73. The shaft carries the roller 69, the periphery of which is shaped to engage the folded or interlocked flanges and roll them into close engagement with the side wall of the body A. The roller 69 may be provided with a flanged portion 69^a which extends inwardly of the folded over flanges, thereby guiding the body as it rotates and preventing its outward movement and also preventing spreading of the seamed flanges outwardly beyond the plane 90 of the head a. At its upper end, the bracket 70 is provided with a cross head 74 in which is formed a screw threaded opening. 75 indicates a screw fitting the screw threaded opening in the cross head and carrying a wheel 100 or other suitable device 76, whereby the screw may be rotated. The free end of the screw 75 engages the slide 71 to force it downwardly

toward the body A to effect pressure of the roller 69 upon the seamed flanges 18 and thus insure their complete rolling down against the body side wall.

- 5 Where the body A is formed with a recess to receive the seam and provide a substantially flush side wall for the completed container, the mandrel 68 is formed with recess 68', as shown in Fig. 1^a.
- 10 The supporting member may be removably mounted on the shaft 58 so that members having any desired diameter and length may be mounted thereon.

The bracket 70 is held in position by the 15 clamping members 71^a, 71^a, which may be adjusted longitudinally of the rod 59 to position the seaming device or roller 69 in operative relation to the mandrel 68. The members 71^a, 71^a, are adjustably secured to 20 the rod 59 by suitable bolts 70^b engaging aligned flanges provided on the opposite sides of the clamping members 71^a. The rod 59 is adjustably held by the bearings 57 in a similar manner so that adjustment of the 25 roller 69 relative to the mandrel can be effected by adjusting the bracket on the rod 59 or by adjusting the latter endwise in the bearing members 57.

In my form of construction the shaft 58 30 and rod 59 are relatively long and their respective supports are spaced from each other so that the effective pressure required to roll down the folded seams into final form and condition, even on relatively thick gage metal, 35 will be adequately resisted.

In my form of construction it will be noted 40 that the mandrel is within the container and the rolling down roller is aligned therewith, so that they may co-act to roll the flanges into a seamed joint on or around the side wall of 45 the body; and also that the roller is shaped to co-operate with the mandrel with the result that the body A is held thereon without the use of clamping devices and the folded portions of the seam, or any of them are prevented 50 from bulging laterally or outwardly relative to the surface of the head a.

To those skilled in the art to which my invention relates, many changes in construction 55 and widely differing embodiments and applications of the invention will suggest themselves without departing from the spirit and scope thereof. My disclosures and the description herein are purely illustrative and 60 are not intended to be in any sense limiting.

What I claim is:

1. In apparatus of the class described, the

combination with a frame, of a pair of members supported on said frame in relatively stationary, parallel relation, corresponding 60 ends of said members extending outwardly from said frame, the extended end of one of said members carrying a mandrel adapted to support a container body and head having their flanges in interlocked relation, means for rotating the mandrel carrying member, a support on the extended end of the other member and provided with guides disposed perpendicularly to the axis thereof, a slide 65 movably engaging said guides, a roller on said slide co-acting with said mandrel for rolling down said flanges, and means for operating said slide.

2. In apparatus of the class described, the combination with a frame, of a pair of members supported on said frame in relatively stationary, parallel relation, corresponding 70 ends of said members extending outwardly from said frame, the extended end of one of said members carrying a mandrel adapted to support a container body and head having their flanges in interlocked relation, means for rotating the mandrel carrying member, a support adjustably mounted on the extended 75 end of the other member and provided with 80 guides disposed perpendicularly to the axis thereof, a slide movably engaging said guides, a roller on said slide co-acting with said mandrel for rolling down said flanges, and means for operating said slide.

3. In apparatus of the class described, the combination with a frame, of a pair of members supported on said frame in relatively stationary, parallel relation with corresponding 85 ends thereof extending outwardly from said frame, one of said members being rotatable in said frame and carrying on its extended end a mandrel adapted to support a container body and head with their flanges in interlocked relation and the other member being movable in an endwise direction relative to said frame and said first mentioned member, means for adjustably securing the last mentioned member to said frame, means for rotating the first mentioned member, a support on the extended end of said endwise movable member and provided with guides disposed perpendicularly to its axis, a slide 90 movably engaging said guides, a roller on said slide for rolling down said flanges, and means for operating said slide.

In testimony whereof, I have hereunto subscribed my name.

ANTHONY SCHROEDER.
